PICKER

Charles Walter Yelm, Denver, Colo., assignor to
The Gates Rubber Company, Denver, Colo., a
corporation of Colorado

Application October 16, 1941, Serial No. 415,175

1 Claim. (Cl. 139—159)

This invention relates to improvements in pickers of the type employed in connection with looms.

Every power operated loom is equipped with automatic means for transferring the shuttle through the shed of the warp and this means comprises interconnected picker staffs to each of which is secured a picker that receives the shuttle and imparts to it a sufficient speed or momentum to return it to the opposite side of the loom.

Since shuttles are quite heavy and are equipped with conical steel points, the continuous stopping and acceleration of shuttles during the weaving operation imposes an enormous strain on the pickers and many inventions have heretofore been made for the purpose of improving the picker constructions to the end that they will have a longer life and operate more satisfactorily than at present.

It is customary to provide pickers with an elastic or resilient body having an opening for the reception of the conical shuttle end as such resilient bodies, normally constructed from rubber composition or rubberized fabric, cushion the blow due to the stopping of the shuttles.

It is the object of this invention to produce a picker constructed in part of metal and of such a design that a resilient picker body can readily be inserted in a cup-like holder and be readily removed therefrom when badly worn. Such pickers can be permanently attached to the picker staffs and when the elastic body is worn, it can be removed and replaced by a new one and in this way the adjustment of the picker is not interfered with and the substitution of a new for a worn picker body can be effected quickly whenever this becomes necessary.

In order to explain the invention more clearly so that its construction and advantages can be more readily understood, reference will be had to the accompanying drawing in which the invention has been illustrated in its preferred form, and in which:

Figure 1 is a fragmentary view showing a portion of a power operated loom and showing the shuttle in operative engagement with the picker;

Figure 2 is a side elevation of my improved picker, the position of the picker staff relative to the picker being indicated by broken lines;

Figure 3 is a front elevation of the picker shown in Figure 2;

Figure 4 is a section taken on line 4—4, Figure 3;

Figure 4a is a fragmentary section similar to that shown in Figure 4 and shows a slightly modi-

fied form of means for securing the picker body in place;

Figure 5 is a side elevation similar to that shown in Figure 2, and shows a slightly modified means for securing the picker to the picker staff;

Figure 6 is a top plan view taken along line 6—6, Figure 5;

Figures 7 and 8 are respectively a side elevation and the front elevation of the replaceable picker body showing the same detached from the holder;

Figure 9 is a side elevation showing a slightly modified form; and

Figure 10 is a section taken on line 10—10, Figure 9.

In the drawing reference numeral 10 designates a floor or other base on which a power operated loom is supported. Reference 11 designates the lower end of a loom member or support while reference numeral 13 designates a shuttle receiving shelf of which one is positioned on each side of the loom. The warp has been designated by reference numeral 14, while the picker staff has been designated by reference numeral 15. A sweep 16 connects the picker staffs on opposite sides of the loom and this is operated by suitable cams not shown. The lower end of the picker staff is mounted on a rocker 17 supported on the outer end of bracket 18 in such a manner as to impart to the upper end a straight line motion during operation. The shuttle has been designated by reference numeral 19 and the picker by reference numeral 20.

Referring now to Figures 1, 2, 3 and 4, it will be seen that the picker which forms the subject of this invention, consists of a frusto-conical cup-like holder 21 which may be formed from soft steel or some other suitable metal. In the drawing the wall of the holder has been shown as tapered to an appreciable extent, but the taper may vary between quite wide limits. The degree of taper shown in Figure 2 is believed to be quite suitable although it may be varied so as to obtain the best results.

The smaller end of the cup-like holder is electro-welded or otherwise attached to a U-shaped member comprising the two parallel sides 22 and the interconnecting end portion 23. The sides 22 are spaced apart a proper distance to receive between them the picker staff 15 and are provided with three or more holes for the reception of bolts 24 by means of which the picker is secured to the picker staff. Positioned within the holder is a picker body 25 which is constructed of suit-

ably compounded rubber composition either free from fiber or mixed with cotton fiber in any desired degree. It may also be formed from rubberized fabric or other material found to be suitable for this purpose. The body 25 is made of the proper size and shape to fit the interior of the holder and, in the embodiment shown in Figures 2 and 4, is provided on diametrically opposite sides with depressions 26 into which the inwardly extending anchoring lugs 27 project as shown. The depressions 26 and the lugs 27 serve to position the body rotarily relative to the cup and to hold it in position during operation. The front end of the picker body has a depression 28 for the reception of the pointed end of the shuttle. When the picker body has been worn to such an extent that replacement seems to be indicated, a tool, such as a screw driver or similar tool indicated by reference numeral 29 in Figure 3, is inserted into the opening 30 provided for this purpose in the wall of the holder. The wedging action of this tool serves to move the body outwardly so that it may be entirely removed from the holder and provide space for the replacement body.

In the construction shown in Figures 2 to 4, the lugs 27 are formed by bending inwardly the metal between two parallel slits 31.

In Figure 4a a slightly different form of holding means has been shown and in this modification the tongue 27 has been cut entirely loose at its inner end and the cut end 32 bent inwardly. End 32 can be forced into the body 25 and serves to anchor the same against removal. When the body 25 is to be removed an instrument is inserted into the concave portion 33 and the tongue moved outwardly after which the body is pried loose by means of the tool 29 already referred to.

In Figures 9 and 10 another means is shown for securing the picker body in the holder. The wall of the holder is provided with two openings 38 and the body 25 with correspondingly positioned tapered lugs 39 that interlock with the walls of the openings in the manner shown in Figure 10. When the body is to be removed the lugs are forced inwardly by means of a suitable tool after which the body 25 is pried loose as above explained. Attention is called to the plate 23a which extends above and below the holder and which is provided with holes for screws or bolts by means of which it is attached to the front of the picker staff. The sides 22 can be dispensed with when plate 23a is used. The specific construction of the cup-like holder may vary from that shown as long as it performs the same function.

Particular attention is directed to Figure 10 and to the specific shape of the lugs 39. It will be observed that the side towards the rear, or the left in Figure 10, tapers gradually whereas the other side makes an angle of slightly more than ninety degrees with the surface of the picker body. The long rearward taper facilitates insertion and the short slightly inclined outer end of the lugs permit the lugs to engage the outer walls of the openings and to automatically adjust themselves so that they will always be in engagement with the opening wall; this assures that the resilient bodies 25 will always be firmly held in position.

The body 25 is constructed of such a size that it will require considerable force to insert it in the holder and therefore when it is once in place,

it will remain in that position until it is to be replaced by another.

Since the picker body 25 is formed from a rubber composition or a rubber containing material 5 vulcanized to the desired hardness, it will tend to expand transversely as well as compress axially when accelerating the shuttle. Due to the outwardly flaring recess the force that tends to expand the picker body will be resolved by the inclined wall into a radial and an axial component, the latter serving to resist axial compression.

In the drawing the angular inclination of the holder wall is less than the angle of repose between the rubber composition and metal and the body 25 will therefore remain in place in the absence of anchoring means. When the angle of the conical surfaces is greater than the angle of repose anchoring means must be employed.

In Figures 5 and 6 I have shown a slightly modified means for securing the holder to the picker staff. In this modification the sides have been designated by reference numeral 22a and extend to the rear of the picker staff where they are reversely bent, each one forming an S-like section 25 whose convex portions have been indicated in Figure 6 by reference numerals 34 and 35. The extreme ends 26 are provided with openings for the clamping screws 37. It is apparent that with a construction like that shown in Figure 6, the screws 37 serve not only to move the sides 22a towards each other, but they also serve to move the convex portions 35 towards the right when viewed as in Figure 6 and thus make a clamping contact with the picker staff both along its sides 35 and edges.

It is apparent that other means may be devised for securing the picker to the picker staff and the three means shown and described herein are merely illustrative of means for this purpose and 40 are not to be considered as in any way limiting the invention to such means to any greater extent than necessary by the scope of the claim and the state of the prior art.

From the above description it will be apparent 45 that a picker constructed in accordance with this invention can be adjusted once for all on the picker staff and when the picker body is worn, it can be quickly replaced by a new one which will 50 occupy exactly the same position relative to the shuttle and shuttle table and will therefore obviate the necessity of making adjustments such as are necessary when the entire picker is removed and replaced by another as is now quite generally done.

By means of the construction shown on the drawing and described herein, the cost of maintaining the pickers in first class condition is greatly reduced because it merely involves the 60 replacement of the worn body 25 by a new picker body and since these picker bodies are reenforced by the substantially circular wall of the holder, they do not break down in the way now so common with pickers constructed of rubberized fabric or leather.

Since the part of the picker that is really subjected to the greatest strains comprises only a small portion of the picker as a whole, it is evident that the present practice of removing the 70 entire picker and replacing it with a new one is wasteful of material and involves an unnecessary expenditure as compared with the picker that forms the subject of this invention in which the part that receives the greatest strains is made 75 readily removable and replaceable.

In the drawing three specifically different means have been shown for attaching the holder to the staff and other means may no doubt be devised; it is therefore evident that any suitable means must be included in this invention.

Having described the invention what is claimed as new is:

A picker comprising, in combination a cup-like holder for the reception of a picker body, and

means extending from the closed end of the holder for securing it to a picker staff, said means comprising two spaced, substantially parallel plates having their ends bent towards each other and substantially S-shape, the extreme ends being adjacent the center and provided with openings for a bolt.

CHARLES WALTER YELM.
